UNITED STATES PATENT OFFICE.

JOSEPH BURNETT, OF MONTREAL, QUEBEC, CANADA.

PAPER-HOLDER.

SPECIFICATION forming part of Letters Patent No. 366,200, dated July 12, 1887.

Application filed August 31, 1886. Serial No. 212,343. (No model.)

To all whom it may concern:

Be it known that I, JOSEPH BURNETT, of the city of Montreal, district of Montreal, Province of Quebec, Canada, have invented 5 new and useful Improvements in Paper-Holders; and I do hereby declare that the following is a full, clear, and exact description of the same.

This invention has reference to an improved 10 construction of paper-holder on which are filed and kept in order letters, invoices, and other mercantile or legal documents, &c.

The particular features or combination of 15 parts which form the subject-matter of the present invention will be hereinafter fully set forth and claimed.

In the drawings hereunto annexed similar 20 letters of reference indicate like parts, and Figure 1 is a plan of a paper-holder on which are collected letters or documents, &c. Fig. 2 is an end elevation of the paper-holder shown in Fig. 1. In this figure the board *s* is represented as slightly inclined—that is to say, in the position indicated by the dotted 25 line *l* in Fig. 3. Fig. 3 is a side elevation of the paper-holder shown in Fig. 1. Fig. 4 is a plan, part in section, on line *y* *y*, Fig. 3, with board *s* removed. Fig. 5 is an isometrical view of the parts by which the documents are 30 held in place on the paper-holder. Fig. 6 is an isometrical detail of the file. Fig. 7 is a side elevation of the punching mechanism, taken partly in section on line *x*, Fig. 2. Fig. 8 is an isometrical view of the "binder" for 35 holding the file, and letters, &c., placed thereon after the file has been filled. Fig. 9 is an isometrical view of the catch.

Before beginning the particular description 40 of the construction of my invention I would explain that the letters or documents to be filed are first collected on a file secured in a paper-holder, which said file after it has been filled is removed from the paper-holder and, with the documents upon it, secured in a binder, 45 another file being supplied and secured in the paper-holder; and so on as many files may be supplied and filled in the paper-holder as may be desired.

I will begin with the description of the 50 paper-holder.

Letter *a* is a board of suitable dimensions,

at the top of which is attached a frame-work, *b*, and at the foot of which is attached the punching mechanism *c*. The frame-work *b* consists of a base, *d*, the lower ends of which are formed into sockets *e*. Made integral with the base *d* are three projections, *f*, *g*, and *h*. These are bound together at their upper extremities by a cross-bar, *i*. The projections *f* and *h* are provided with arms *k*, and the projection *g* is provided with a slot-opening, *l*. 60

m is an eye formed upon the base *d*, for hanging the whole apparatus up by.

In the slot-opening *l* is placed a slide, *n*, which is free to move up and down, and to be 65 secured in position by an ordinary screwed thumb-nut, *o*. On the slide *n* is formed an arm terminated in an eye, *p*, and to it is pivoted an arm terminated in an eye, *q*, at one end and a flange, *r*, at the other. (See Figs. 70 1, 3, and 5.) To the flange *r* is attached a board, *s*, the lower edge of which engages with ordinary graduated spring-catches, *t*.

The file (see Fig. 6) consists of a base-piece, *a'*, provided with projections *b'*, fitted to be 75 received within the sockets *e*, openings *c'* being formed in the sockets *e* and projections *b'*, so that by the pins *d'* the base *a'* is rigidly attached to the base *d*.

s' is a projection formed on the base *a'* or 80 not, as desired. As shown in Figs. 2, 3, 4, and 5, it is present. As shown in Figs. 6 and 8, it is absent. When present, it serves as the means for removing the file from the sockets *e*, by providing a surface upon which to press 85 (upon the top of it) and force the projections *b'* out of the sockets *e*.

In the base *a'* are secured the tubes *e'*, in the position and of the relative height shown, and when the file is in position the tubes *e'* are immediately under the ends of the arms *k*. (See 90 Figs. 3 and 5.) To the ends of the arms are pivoted swinging bars *f'*, preferably provided with pointed ends, (but beveled ends might be used,) to agree with the beveled ends of the 95 tubes *e'*, and so arranged as to the pivots *g'*, that they may be turned to the positions indicated by dotted lines in Fig. 2.

With regard to the punching mechanism *c* shown, as I do not claim any invention in it 100 *per se*, it will suffice to say that it is of a double form arranged to punch two holes in the top

of the letter or document to be filed, of suitable size and distance apart to agree with the size and distance that the two tubes e' are apart.

5 In Fig. 8 is shown all that is necessary to illustrate a binder of suitable size to receive the file after it has been filled with letters or documents.

In one end of the binder is provided two 10 sockets, a^2 , to receive the projections b' of the file. These are so arranged that when the projections b' are put into position with them, as shown in Fig. 8, the holes c' (see Fig. 6) are sufficiently beyond the sockets a^2 to allow of 15 the introduction of the pins b^2 , which in this case are preferably made integral with a bar, c^2 , (see Fig. 9,) but not necessarily so made, as they might be separate pins similar to the pins d' , only longer.

20 The pins b^2 are made sufficiently long not only to pass through the projections b' , but also through the bottom c^5 of the binder, and are about flush with its under side. I here wish to remark that I do not confine myself to the 25 precise means above described for securing the file in the sockets a^2 , as quite a quantity of contrivances may be arranged for this purpose, which would be equivalent to what I have described.

30 e^2 is a bar. This is hinged, as shown by dotted lines at f^2 , to the binder d^2 , and provided with any suitable catch, g^2 , for holding its other extremity down in the recess h^2 .

i^2 is a cover, hinged to the binder d^2 in any 35 ordinary manner, of suitable size to form a proper cover to the binder.

k^2 is a removable bracket, which may at pleasure be placed in connection with the binder and file, as shown in Fig. 8, being secured by a clamp, l^2 , and set-screw m^2 .

40 The operation of my invention is as follows: The board s is first turned up from the position shown in solid lines in Fig. 3 to that indicated by dotted lines in the said figure. 45 The letters or documents to be filed are first introduced to the punching mechanism and punched. They are each afterward taken and bent transversely to the form of the curved line 2 in Fig. 2, the edges of the paper being 50 brought to the positions shown at 3 3. The swinging bars f' are by the edges of the documents slightly pushed on one side and the document straightened out to the position indicated by the dotted line 4 4, whereupon the

55 holes that have been punched in it are passed down over the tubes e' , the swinging bars f' returning by gravity to their normal position.

After a sufficient number of letters or documents have been placed upon the tubes e' , the 60 board s , being held at the top end by the flange r and at the bottom end by the catches t , is brought down to press upon the letters and documents, and thus by keeping them continually pressed any creases or the like that may 65 be in them are gradually taken out and the papers rendered compact or dense on the file.

As they increase, the position of the slide n in the slot l may be raised the amount required for the one end of the board s , while the other end of the board s may be engaged with a 70 higher notch in each of the catches t , thus adjusting the board s to the increased thickness of papers on the file. When the file has been filled, and it is desired not to place any more documents on it, the pins d' are withdrawn, 75 the projections b' are drawn out of the sockets e , and another file placed in the sockets e , as before. The file with letters or documents on it is then introduced and placed with its projections b' in the sockets a^2 , as shown in 80 Fig. 8. These are secured in place by the pins b^2 of the bar c^2 , the bar c^2 being raised while the file is being put in place, by turning it on its hinge f^2 ; and when the file is in place, with the documents, the bar c^2 is turned down to 85 the position shown in Fig. 8 and secured with an ordinary catch, g^2 .

I would here explain that with regard to the paper-holder shown by Figs. 1 to 6, inclusively, a number of the files shown in Fig. 6, 90 and a number of binders, d^2 , illustrated by Fig. 8, may be provided to one paper-holder, so that when the file in the paper-holder becomes full it may be removed to a binder and another file placed in the paper-holder. 95

The letters and documents when placed in the binder d^2 may be said to be permanently filed for being placed in a safe or other place for safe keeping; but as in the practice of everyday life it sometimes becomes necessary to 100 remove from the file in the binder certain letters or documents which may have been considered no longer required, I will now explain how this will be done, either from the file in the paper-holder or from the file in the 105 binder.

First, as regards the file in the paper-holder. To remove a lower document, it is only necessary to turn up the board s to the position shown by dotted lines in Fig. 3, and turn up 110 all the documents that are situated on the file above the one required to be removed until they are upon the arms k , where the board s will form a rest for them. Then by turning the swinging bars f' slightly the paper may be 115 removed from the file, after which the letters or papers that have been placed on the arms k may be returned to their position on the file and the board s turned down to press upon them. 120

Second, as regards the file when placed in the binder. For this purpose the bracket k^2 , having arms k and clamp l^2 , is provided and put in place, as shown in Fig. 8, after which any document or paper may be removed from the file in substantially the same manner as herein first above described, only that it is necessary to raise the bar c^2 in the first place out of the way by turning it up on its hinge f^2 . 125

I wish to observe that one bracket k^2 and arms k will serve for a large number of binders provided with files of equal size. 130

I am aware that it is not new to form a single arm, k , having a swinging bar, f' , attached thereto by a spring and arranged to combine with a projection or standard situated in relation to the said bar f' , as hereinbefore described for my tube e' ; but my invention goes further than this, and provides two swinging bars, f' , set to swing or open in opposite directions to one another, as shown by dotted lines in Fig. 2, by which, when it is desired to turn up a quantity of the papers from the tubes e' to the arms k , to get at a lower paper, all danger of the papers coming off the file at the upper end of the tubes e' is prevented, and loss of time in taking extra care is saved, for should the swinging bars f' be both made to swing in the same direction, either to the right or to the left, back or front, (we will say they are made to both swing to the right,) then a lateral motion of the papers to the right in moving them from the tubes e' to the arms k would cause the swinging bars f' to swing and open a space between their lower ends and the upper ends of the tubes e' , and some of the papers would be in danger of coming off the file, and so it would be in whatever direction they were both made to swing. This is looked upon as an important advantage, as it would be a very serious objection to have the papers come off the file when they are not required to do so.

What I claim, and wish to secure by Letters Patent, is as follows:

1. The combination of the board a , two arms, k , and two tubes, e' , secured thereon, substan-

tially as described, and two swinging bars, f' , pivoted to arms k , set to swing in different directions, the whole arranged substantially as described; for the purposes set forth.

2. The combination of the board a , arms k , swinging bars f' , attachable and detachable base a' , having tubes e' , the whole constructed and arranged substantially as described.

3. The combination of the board a , arms k , bars f' , detachable base a' , having tubes e' , and board s , the whole constructed and arranged substantially as described, for the purposes set forth.

4. The combination of the board a , base d , having projections f and h , and projection g , having slot l , also having sockets e , arms k , bars f' , base a' , having projections b' , and tubes e' , slide n , having arm and eye p , arm having eye q and flange r , board s , and catches t , the whole constructed and arranged substantially as described.

5. The combination of the binder d^2 , file secured therein, as described, with removable and replaceable bracket h^2 , having arms k , and swinging bars f' , the whole constructed and arranged substantially as described, for the purposes set forth.

6. The combination of the binder d^2 , having bar e^2 , and sockets a^2 , file, as described, bracket h^2 , arms k , and bars f' , the whole arranged and operating substantially as described.

JOSEPH BURNETT.
